(57) **CLAIM**

The ornamental design for an ion solenoid circuit board, as shown and described.

DESCRIPTION

FIG. 1 is a perspective view of an ion solenoid circuit board; FIG. 2 is a top plan view of an ion solenoid circuit board; FIG. 3 is a left side elevation view of an ion solenoid circuit board;

FIG. 4 is a front elevation view of an ion solenoid circuit board;

FIG. 5 is a right side elevation view of an ion solenoid circuit board; and,

FIG. 6 is a bottom plan view of an ion solenoid circuit board. The broken line showing of the environment is for illustrative purpose only and forms no part of the claimed design.
